BENJAMIN ROBINSON, OF BOSTON, MASSACHUSETTS.

Letters Patent No. 94,516, dated September 7, 1869; antedated August 21, 1869.

IMPROVED RAILWAY-RAIL SPLICE.

The Schedule referred to in these Letters Patent and making part of the same.

To all whom it may concern:

Be it known that I, BENJAMIN ROBINSON, of Boston, in the county of Suffolk, and State of Massachusetts, have invented a new and useful Improvement in Railroad-Rails, of which the following is a full, accurate, and complete description, sufficient, with reference to the accompanying drawings, to enable the invention to be carried into effect.

To make a firm joint at the place where rails come together, so that rolling stock will pass over the joint noiselessly and easily, to reduce the abrasion of the ends of the rails, allow of expansion to a sufficient degree, and at the same time reduce the cost of track-laying, is the present desideratum, and is my object in this invention.

The principal feature of this joint is an arrangement of projections and depressions upon the sides of a rail, bevelled so as to form a lap-splice toward the end, the projections fitting into the depressions of the abutting rail, and the two abutting rails bolted together.

By reference to the drawings, the device can be understood more readily.

Three forms or variations are there shown, all involving the principle of the invention, and all showing the manner of carrying it out.

Figures 1, 4, and 8, are top plans of a joint on my principle.

R and R' are, in each drawing, rails. The web of these rails is shown in dotted longitudinal lines. The example taken is a T-rail. The ends of these rails are so formed at the joint as to follow on top the lines x y y' x', and the web of each rail is transferred from its centre to its exterior. This is shown by reference to the sections shown in Figures 2, 3, 6, 7, 10, 11. The stiffness of the rail is thus preserved, and the T-rail assimilates the form of a half U-rail at the end.

In the rail, if of the form shown in fig. 1, a section taken at c c, or at the centre of the joint, shows us the web of rail R crowded to the left in fig. 3, with a depression made in it, as shown at g h i, and having the plan k l m n, of fig. 1.

The web of rail R' is crowded to the right, at seen at o, fig. 3, and has formed on it a hook, of the section g h i, which fits into the depression in rail R.

Two bolts, p and q, fig. 1, fasten the rail together, the bolt-holes in the thin ends of the rails being so slotted as to allow expansion, and the tongue or projection on rail R' being shorter than the depression in rail R, any pressure on rail R' will, with this form of tongue, (hooking,) draw rail R closely up and make a close joint.

This device may be modified, as shown in figs. 4, 5, 6, and 7, the principle involved being retained.

A tongue and depression are formed on each rail R and R', the plan of which, instead of being a rectan-

gle, is a triangle, w y z, w y' z', the line z z' being the medium line of the rail, and the projection being, in every instance, toward the tip, the depression toward the butt of the bevel-splice.

The sections, figs. 6 and 7, are similarly lettered to fig. 3.

On whichever rail weight is thrown, the other is drawn closely to it.

The secondary form, shewn by figs. 4, 5, 6, 7, is readily converted into the tertiary form, shown in figs. 8, 9, 10, 11; simply by changing the sectional shape of the tongue and depression g h i, figs. 6 and 7, to the sectional shape a b c d, of figs. 10 and 11, and their ground plans from w y z, w y' z', triangles, to rectangles, like those in fig. 1, k l m n.

The bolt p, in both the secondary and tertiary form, is put through at the centre of this joint, and but one bolt is required. The bolt-hole in one rail requires, of course, to be slotted, to allow for expansion, and the locking tongues k l m n, of fig. 8, must be shorter than the depressions into which they fit, for the same reason.

In considering the principle of this rail, and the manner in which these three forms glide into each other, it is necessary, first, to notice the fact that the inclined planes y y', in case of the contraction of the rail, would not slide along each other, and thus make a continuous rail, were there not some contrivance by which they shall be brought together and held. This is furnished by the tongues g h i, of the primary and secondary forms, with their downward-pointing inclined planes hooking into the depressions g h i, of figs. 1 to 7. In the tertiary form, this would be effected by making the bolt-head rest on an inclined plane surrounding the slot through which the bolt passes, said plane being parallel to the joint-line y y'.

There is another advantage in this form of rail. The mortises and tenons locking sidewise across the dividing-line of the joint, frame the two rails into one continuous rail, support every part of it, and avoid brooming, while the diagonal joint-line will never allow a shock as the carriages roll over the rail, because the wheels always have a support upon the rail on either side of the gap or opening.

As I am aware that railroad-joints have heretofore been made by notching and lapping the ends of the rails, and notably in the device of James R. Hilliard, patented May 13, 1856, I do not intend to claim more than the particular system shown, of interior mortises and tenons, and specially disclaim a joint having a lateral lap only, or a lateral combined with a vertical lap on planes parallel with the longitudinal axis, or the slope of the vertically-lapping surfaces toward the centre of the rail.

I claim, and desire to secure by Letters Patent—
1. The railroad-rail, formed at the end with a lat-

eral bevel, as shown $x y y' x'$, with mortises and tenons on the bevelled side, when arranged to keep the inclined planes $y y'$ in contact with each other, by means of compensating inclined planes $g h$, substantially as described.

2. The railroad-rail, formed at the end with a lateral bevel, when a mortise or tenon, or both, are ar-

ranged upon the bevelled side, to lock with a corresponding mortise or tenon, or both, in the abutting rail, substantially as described.

BENJA. ROBINSON.
